United States Patent

Des. 241,698

Patented Oct. 5, 1976

241,698

FURNITURE BASE

Adger S. King, Jr., Box 223 Lincoln Blvd.,
East Moriches, N.Y. 11940

Filed Apr. 4, 1975, Ser. No. 565,081

Term of patent 14 years

Int. Cl. D6—06

U.S. Cl. D6—194

FIG. 1

FIG. 2

FIG. 3

FIG. 4

FIG. 1 is a perspective view of a furniture base embodying my new design.

FIG. 2 is a top view of the furniture base of FIG. 1 to a reduced scale.

FIG. 3 is a bottom view of the furniture base of FIG. 1 to a reduced scale.

FIG. 4 is a side elevational view of the table base of FIG. 1 to a reduced scale.

I claim:

The ornamental design for a furniture base, as shown.
